END CAP FOR AN ELECTRIC PRESSING IRON HANDLE

Moises B. Lorenzana, Glen Ellyn, Ill., assignor to Sunbeam Corporation, Chicago, Ill., a corporation of Illinois

Filed May 1, 1968, Ser. No. 11,734

Term of patent 14 years

Int. Cl. D7—06

U.S. Cl. D49—6

FIG. 1 is a perspective view of an end cap for an electric pressing iron handle embodying my new design;

FIG. 2 is a top plan view thereof;

FIG. 3 is a rear elevational view thereof; and

FIG. 4 is a side elevational view thereof.

The broken lines in FIG. 1 are shown for illustrative purposes only.

I claim:

The ornamental design for an end cap for an electric pressing iron handle, as shown and described.
